UNITED STATES PATENT OFFICE

2,046,454

SLOT FORMING MACHINE

George Hazelton, Cyril Harry James, and William Isaac Bacon, Leicester, England, assignors to United Shoe Machinery Corporation, Paterson, N. J., a corporation of New Jersey

Original application December 23, 1933, Serial No. 703,730. Divided and this application December 19, 1934, Serial No. 758,164. In Great Britain July 1, 1933

5 Claims. (Cl. 12—42)

This application relates to the manufacture of shoes and is illustrated as embodied in a machine for forming slots in heels.

In United States Letters Patent No. 1,984,453, granted December 18, 1934 on an application filed in the names of Bates et al., there is disclosed an improved method of shoemaking in which heels built up from lifts are trimmed to shape and are preferably scoured before attachment to the shoes. One method of attaching such heels to shoes provided with short soles is disclosed in United States Letters Patent No. 2,027,431, granted January 14, 1936, on an application filed in our names, of which this application is a division, and comprises forming a bevel at the rear end of the sole and cutting in the breast of the heel a deep slot which is of suitable shape to receive the rear end of the sole, the slot extending transversely of the heel and having one of its sides terminating substantially at the front edge of the attaching face of the heel.

It is an object of this invention to provide a machine for quickly and effectively forming slots such as above described in the breasts of heels. With the above object in view, and in accordance with a feature of this invention, the illustrated machine is provided with a rotary barrel cutter, a supporting member constructed and arranged to be engaged by the forward end of the attaching face of a heel, gages secured to the member and having heel-engaging faces respectively arranged to engage opposite sides of the heel thereby to position the same widthwise of the member, and stops for positioning the heel lengthwise of the member, the member being mounted for movement in a predetermined path to move the heel against the cutter thereby to form in the breast of the heel a slot extending transversely of the breast and formed and arranged to receive the rear end of a short sole.

In the drawing,

Fig. 1 is a side elevation with parts broken away in an illustrative machine for forming a sole-receiving slot in the breast of a heel;

Fig. 2 is a plan view of the machine the cutter of which is shown in section;

Fig. 3 is a sectional view of the machine taken along line III—III of Fig. 1; and

Fig. 4 is a perspective view of a heel which has been slotted by the use of the above machine.

In the above-mentioned United States Letters Patent No. 2,027,431, there is disclosed and

claimed a heel 20 which comprises a plurality of lifts 22 of leather or other suitable material and is finished prior to being attached to the shoe. The illustrated machine is constructed and arranged quickly and effectively to form in the breast 24 of the heel a slot or groove 26 shaped and arranged to receive the rear end of a short sole (not shown) in order to fit the heel to the shoe as disclosed in United States Letters Patent No. 2,027,431. The slot 26 is of V-shaped construction in accordance with the shape of the rear beveled end of the sole. The slot 26 is bowed upwardly to correspond to the curvature of the shank portion of the sole of the shoe and extends from one side of the heel to the other. The upper face of the slot 26 terminates substantially at the forward edge 28 of the attaching face 30 of the heel and forms therewith a wedge 32 which is positioned between the beveled end of the sole and the shoe upper, the wedge 32 being compressed against the beveled end of the sole during the heel-attaching operation. Heel-attaching nails are driven through the beveled rear end of the sole positioned within the slot 26 while the heel 20 is compressed against the shoe, a tight joint thus being formed between the heel and the sole.

After the heel 20 has been attached to the shoe the marginal edge portions of the beveled rear end which project beyond the sides of the heel are trimmed flush with the respective sides of the heel, the trimming cuts usually extending forwardly at the heel breast line in order to insure that the lateral edges of the shank portion of the sole shall merge attractively with the sides of the heel. The joint between the heel and the shoe is finally operated upon by an abrasive tool in order to smooth the joint.

The slot 26 is formed by moving the heel 20 in a predetermined path against a rotary barrel cutter or saw 34 comprising a plurality of V-shaped teeth 36 and mounted upon a rotatable shaft 38 journaled in suitable bearings (not shown). The teeth 36 of the cutter 34 extend in the general direction of the axis of rotation of the shaft 38 and are arranged in circumferentially spaced relation. Each of the teeth 36 of the cutter 34 is tapered and has a shape similar to the cross section of the slot 26 to be formed. The teeth 36 are preferably about three-fourths of an inch in length and are illustrated as inclined at about 14° to the axis of rotation of the cutter 34. In order to position the heel 20 preparatory to moving the same in a predetermined path, which is disposed in

substantially parallel relation to the axis of rotation of the shaft 38, the machine is provided with a heel support or table 40 mounted for reception within a T-shaped guideway 42 (Fig. 3) 5 of a guide block 44. The guide block 44 is secured to the top of a column 46 which is screwed to a bracket 48, the bracket in turn being screwed to a slide 50 mounted for vertical adjustment in the frame of the machine by turning a screw 52 which is rotatably mounted in the frame and is in threaded relation with the slide 50. Secured to the table 40 are a pair of centralizing gages 54 which are constructed and arranged to position the heel widthwise upon 10 the table, the gages being secured to the table by screws 56 and having depending flanges 58 respectively constructed and arranged for sliding engagement along correspondingly shaped guideways of the table 40. The forward ends 15 of the gages 54 are inturned to form opposing extensions or stops 60 arranged to engage the breast 24 of the heel 20 positioned widthwise upon the table 40.

The opposing faces 62 (Fig. 3) of the gages 25 54 are undercut in order to engage the top portions of the sides of the heel. The table may have a convex member 64 secured thereto by screws 66 in order to engage a substantial portion of the attaching face of the heel, the convex member cooperating with the undercut sides 30 62 of the gages 54 rigidly to secure the heel to the table during the slot-forming operation.

Movement of the table 40 toward the cutter 34 is limited by a nut 68 which is in threaded 35 engagement with a rod 70 secured to the rear end of the table 40. The rod 70 passes through a recess 72 of an angle arm 74 secured to the guide block 44 and as the table 40 is moved to the right (Figs. 1 and 2) the nut 68 engages 40 the angle arm 74. Rearward movement of the table 40 is limited by direct engagement of the table with the angle arm 74, the table being normally held away from the cutter 36 by a spring 76 the upper end of which is secured 45 to the table 40 and the lower end of which is secured to the guide block 44. It will be noted that the forward inner portions of the gages 54 are cut away to provide arched portions 78 (Fig. 1) to prevent the gages from engaging the cutter 36 as the table is moved toward the same 50 in a direction parallel to the axis of rotation of the shaft 38.

In order to perform the slotting operation the operator places the heel 20 attaching face downwardly upon the table 40 between the centralizing gages 54 and moves the heel to the right (Figs. 1 and 2) until the breast 24 of the heel engages the projecting portions 60 of the gages 54 respectively. Continued movement of 55 the heel 20 to the right causes the same and the table 40 to slide as a unit in a rectilinear path along the guideway 42 of the guide block 44 against the cutter 36 thereby to force the breast of the heel against the cutter. Movement of the table 40 to the right is limited by engagement of the stud 68 with the angle arm 74. The table is then returned under pressure of the spring 76 to its retracted position, 60 the heel then being removed from the table. The gages 54 may be changed if desirable, in accordance with the shape of the heel being slotted. The operating parts of the machine may be enclosed within a casing (not shown) 70 75 which is preferably provided with a suction pipe

(not shown) for removing sawdust from the machine.

Having thus described our invention, what we claim as new and desire to secure by Letters Patent of the United States is:

1. A machine for operating upon heels having, in combination, a rotary barrel cutter, a supporting member constructed and arranged to be engaged by the forward end of the attaching face of a heel, gages secured to the member and having heel-engaging faces respectively arranged to engage opposite sides of the heel mounted upon said member thereby to position the heel widthwise, and stops for positioning the heel lengthwise, said member being mounted 10 for movement in a predetermined path to move the heel against the cutter thereby to form in the breast of the heel a slot extending transversely of the breast and formed and arranged to receive the rear end of a short sole. 20

2. A machine for operating upon heels having, in combination, a rotary cutter, a table for engaging the attaching face of a heel, and gages secured to the table and having heel-engaging faces arranged to engage the opposite 25 sides respectively of the heel thereby to position the same widthwise, each of said gages comprising an extension constructed and arranged for engagement with the breast of the heel to position the same lengthwise of the table, said 30 table being mounted for movement under pressure of the heel to cause the heel to move against the cutter thereby to form in the breast of the heel a groove extending transversely of the breast of the heel in close proximity to the 35 forward edge of the attaching face of the heel.

3. A machine for operating upon heels having, in combination, a rotary barrel saw, a table for supporting a heel, said table having a convex surface constructed and arranged to be engaged by the forward portion of the attaching face of the heel, and gages for positioning the heel widthwise and lengthwise upon the table, said table being mounted for movement to present the heel, breast first against the saw 45 thereby to form in the breast of the heel a slot which is positioned adjacent to the attaching face of the heel and is shaped to receive the rear end of the shank portion of a sole. 40

4. A machine for operating upon heels having, in combination, a rotary barrel saw, a table for supporting a heel, said table having a convex surface constructed and arranged to be engaged by the forward portion of the attaching face of the heel, gages mounted upon the table 55 and having undercut heel-engaging faces arranged to engage opposite sides respectively of the heel mounted upon said table for positioning the heel widthwise, and stops for positioning the heel lengthwise, said table being mounted 60 for movement in a predetermined path to carry the heel, breast first against the cutter thereby to form in the breast of the heel a slot extending transversely of the heel and located adjacent to the front edge of the attaching face 65 of the heel.

5. A machine for operating upon heels having, in combination, a rotary barrel saw, a supporting member constructed and arranged to be engaged by the forward end of the attaching face of a 70 heel, gages mounted upon the member and having undercut heel-engaging faces arranged to engage opposite sides respectively of the heel mounted upon said member for positioning the heel widthwise, stops for positioning the heel 75

lengthwise, said member being mounted for movement in a predetermined path to carry the heel, breast first against the saw thereby to form in the breast of the heel a slot extending transversely across the heel and located adjacent to the front edge of the attaching face of

the heel, and a stop for limiting the movement of the member thereby to control the depth of the slot formed in the breast of the heel.
